DESIGN FOR A DISPLAY SIGN

Jack Morgan, Chicago, Ill., assignor to Price Brothers, Inc., Chicago, Ill., a corporation of Illinois

Application March 28, 1947, Serial No. 138,012

Term of patent 7 years

(Cl. D1—12)

To all whom it may concern:

Be it known that I, Jack Morgan, a citizen of the United States, and resident of Chicago, county of Cook, and State of Illinois, have invented a new, original, and ornamental Design for a Display Sign, of which the following is a specification, reference being had to the accompanying drawing, forming a part thereof.

Fig. 1 is a perspective view of a display sign embodying the features of my design.

Fig. 2 is an end elevational view thereof.

Fig. 3 is a top plan view thereof.

The dominant features of my design are shown in full lines.

I claim:
The ornamental design for a display sign, substantially as shown and described.

JACK MORGAN.
